US0D1110378S

(12) **United States Design Patent** (10) **Patent No.:** **US D1,110,378 S**
(45) **Date of Patent:** **** Jan. 27, 2026**

(54) **WAREHOUSE ROBOT**

(71) Applicant: **HAI ROBOTICS CO., LTD.**,
Guangdong (CN)

(72) Inventor: **Wenying Wang**, Guangdong (CN)

(73) Assignee: **HAI ROBOTICS CO., LTD.**,
Guangdong (CN)

(**) Term: **15 Years**

(21) Appl. No.: **29/975,335**

(22) Filed: **Nov. 27, 2024**

(30) **Foreign Application Priority Data**

Sep. 26, 2024 (CN) 202430615629.1

(51) **LOC (15) Cl.** **15-99**

(52) **U.S. Cl.**

USPC **D15/199**

(57) **CLAIM**

The ornamental design for a warehouse robot as shown and described.

DESCRIPTION

FIG. 1 is a front view of a warehouse robot;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof; and,

FIG. 8 is a second perspective view thereof.

1 Claim, 8 Drawing Sheets
